UNITED STATES PATENT OFFICE

PETER A. ALONZO, OF GUADALAJARA, MEXICO

GAUGE FOR ASCERTAINING THE LIFT OF COMPRESSOR AIR VALVES

Application filed November 15, 1930. Serial No. 495,982.

This invention relates to gauges generally, and more particularly to gauges for measuring the lift of all air valves of the Westinghouse steam driven air compressors.

5 The invention has for one of its objects to provide novel gauges of the character stated through the medium of which a skilled or unskilled person may easily ascertain the exact lift of the upper and lower air valves 10 of the compressor.

The invention has for a further object to provide gauges of the character stated which shall be capable of being used efficiently by those engaged in the daily repairing of the 15 air compressors in railroad shops and by those engaged in the up-keep of the compressors in round houses.

The invention has for a further object to provide gauges of the character stated which 20 shall be simple, strong and durable, which shall be uniformly accurate, which shall be capable of being manufactured at a low cost and which shall be adapted to be maintained in a highly efficient condition with little 25 labor and at low cost.

With the foregoing and other objects in view, the nature of which will appear as the description proceeds, the invention consists in the construction, combination and arrangement of parts hereinafter fully described and claimed, and illustrated in the 30 accompanying drawings, wherein:—

Figure 1 is a view partly in vertical section and partly in elevation illustrating the 35 first step of the method of using the upper air valve gauge to ascertain the lift of this valve.

Figure 2 is a similar view illustrating the 40 second or final step of the method of using this gauge to ascertain the lift of this valve.

Figure 3 is a top plan view of this gauge.

Figure 4 is a sectional view taken on the 45 horizontal plane indicated by the line 4—4 of Figure 2.

Figure 5 is a sectional view taken on the 50 horizontal plane indicated by the line 5—5 of Figure 2.

Figure 6 is a view partly in vertical section and partly in elevation illustrating the first 55 step of the method of using the lower air valve gauge to ascertain the lift of this valve.

Figure 7 is a similar view illustrating the second or final step of the method of using this gauge to ascertain the lift of this valve, and

Figure 8 is a top plan view of this gauge.

Referring in detail to the drawings, and particularly to Figures 1 and 2, 1 designates a fragmentary portion of the upper end of the cylinder of a Westinghouse steam driven air compressor, 2 the upper air valve of the compressor, 3 the seat for the valve and 4 the cap for the valve.

An opening 5 formed in the upper end of the compressor cylinder directly above the valve 2, is provided for the reception of the cap 4 which is screw threadedly engaged with the wall of the opening. The cap 4 is provided with an outer annular flange 6 and an upwardly extending wrench engaging boss 7. The flange 6 contacts with the upper end of the compressor cylinder, and as the cap 4 is turned downwardly to compensate for wear therein, and in the valve 2, the flange wears an annular groove in said end of the cylinder. The groove, which surrounds the opening 5 is designated 8.

The gauge, through the medium of which the lift of the valve 2 may be ascertained, and which is shown in Figures 1 to 5, comprises a metal body 9 of U-form in elevation and of sufficient thickness to give it the required strength and rigidity. The cross bar 10 of the body 9 is provided centrally between its ends with an opening 11 which is arranged in a plane parallel to the planes of the legs 12 of the body. The cross bar 10 has its outer corners notched, as at 13, to provide outwardly facing shoulders 14 which are curved and arranged concentrically to the axis of the openings 11. The shoulders 14 are spaced apart for a distance slightly less than the diameter groove 8.

The legs 12 have their inner sides curved transversely, as shown at 15, and these curved sides are concentric to the axis of the opening 11. The distance between the curved sides 15 is slightly greater than the outer diameter of the standard air valve cap 4, and also greater than the corresponding dimensions of over size air valve caps found

in old Westinghouse air compressors, so as to adapt the gauge for application to either of the caps.

The opening 11 is cylindrical and its diametrical dimension is large as compared with the thickness of the cross bar 10. To permit the opening 11 to be formed therein without weakening the same, the cross bar 10 is of increased thickness at its transverse center, as shown at 16. A tube 17, which is greater in length than the width of the cross bar 10, is slidably mounted in the opening 11. The tube 17 is held against rotation with respect to the cross bar 10, by a rib 18 formed on the wall of the opening 11 and engaging in a groove 19 formed in the outer side and extending longitudinally of the tube. The tube 17 is held against accidental endwise movement with respect to the cross bar 10 by a set screw 20 carried by the enlarged cross bar portion 16 and contacting with the tube at a point diametrically opposite the rib 18 and groove 19. That end of the tube 17 located between the legs 12 is of conical formation, as shown at 21, and the other end of the tube is closed by a plug 22 which is screw-threadedly engaged in the tube and provided with a milled operating head 23.

A cylindrical bar 24 is slidably mounted in the tube 17, and extends through and beyond the conical end portion 21 of the tube. The bar 24 is provided at its inner end with a cylindrical head 25 which contacts with the inner surface of the tube 17 to hold the bar against any tilting movement with respect to the tube. The bar 24 is held against rotation with respect to the tube 17 by a rib 26 which is carried by the head 25 and fits in a groove 27 formed in the inner side of the tube and extending longitudinally thereof, the groove 27 being arranged at 90° from the groove 19.

A coil spring 28 which is located within the tube 17 between the plug 22 and rod head 25, functions to constantly urge the bar 24 into its outermost position with respect to the tube. When the bar 24 is in this position the conical outer sides 29 of the head 25 contacts with the conical end 21 of the tube 17. The bar 24 is provided at diametrically opposite sides thereof with series of graduations 30 which are spaced one-thirty-second of an inch apart. The outermost graduation is marked zero, the third graduation from the zero graduation is marked three, and the fifth graduation from the zero graduation is marked five. The outer and smaller end of the conical tube portion 21 functions in connection with the graduations 30 as a pointer or marker.

The valve 2 is provided in the center of the upper side thereof with a one-quarter of an inch tapped hole 31. During the unseating thereof, the valve 2 contacts with the

lower side of the cap 4 and wears away all but that side of the cap alined with the opening 31, with the result that worn caps have central projections, as indicated at 32 in Figure 2. The plug head 23 is provided with a concave recess 33 and the lower end of the graduated bar 24 is provided with a similar recess 34. When the gauge is used one of these recesses receives the lug 32 of the cap 4 so as to enable the lift of the valve to be accurately ascertained.

To ascertain the lift of the upper air valve 2, the valve cap 4 is removed from the cylinder, and the gauge is applied to the cylinder in a manner to position its cross bar 10 upon the upper end thereof and across the opening 5, as shown in Figure 1. In applying the gauge care must be taken to arrange the shoulders 14 in the groove 8 worn in the upper end of the cylinder by the cap flange 6. After the gauge is applied to the cylinder, the set screw 20 is turned back so as to free the tube 17 for downward movement to position the plug head 23 in contact with the center of the upper side of the valve 2. The set screw 20 is now turned up to secure the tube 17 against movement from the position it now occupies on the cross bar 10. After this has been done, the gauge is applied to the valve cap 4 in a manner to position the free ends of its legs 12 in contact with the lower side of the flange 6. While this is being done the graduated bar 24 is held pressed into the tube 27 so as to insure the full contact of these ends of the legs 12 with the cap flange 6. After the gauge has been applied to the valve cap 4, the graduated bar 24 is released so as to permit it to be moved by the spring 28 into contact with the center of the lower side of the valve cap. When the graduated bar 24 comes to rest by contacting with the lower side of the valve cap 4, that graduation 30 located nearest the smaller end of the conical tube portion 21 will indicate the lift of the upper air valve 2. The space between the zero and the third graduations is used for the purpose of ascertaining when an upper air valve is blind; that is, when the air valve lifts less than three-thirty-seconds of an inch. When the graduated bar 24 comes to rest with its third graduation in alinement with the lower end of the tube portion 21, the lift of the valve is correct. The space between the third and innermost graduations is for the purpose of determining the over lift that all worn valves generally have.

Referring to Figures 6, 7 and 8, 1a designates a fragmentary portion of the lower end of the compressor cylinder, 34 the lower air valve of the compressor, 35 the chamber of the cylinder in which the valve works and 36 the cage for the valve. An opening 37 in the lower end of the compressor cylinder is provided for the reception of the cage 36 which is screw-threadedly engaged with the wall of the opening. The cage 36 is provided with

an outer annular flange 38 and a downwardly extending wrench engaging boss 39. The flange 38 contacts with the lower end of the cylinder, and as the cage 36 is turned upwardly, to compensate for wear thereon and in the valve 34, the flange wears an annular groove in the lower end of the cylinder. The groove surrounds the opening 37 and is designated 40.

10 The gauge for ascertaining the lift of the lower air valve 34 is shown in Figures 6, 7 and 8 and embodies parts similar except as to size to the corresponding parts of the gauge for ascertaining the lift of the upper air valve

15 2. The cross bar 10a of the lower air valve gauge is shorter than the cross bar 10 of the upper air valve gauge, the legs 12a of the lower air valve gauge are longer than those of the upper air valve gauge and are provided with concave inner sides 15a, the tube 17a of the lower air valve gauge is longer than the tube 17 of the upper air valve gauge and the plug 22a of the lower air valve gauge is longer than the plug 22 of the upper air valve gauge. The other parts of the lower air valve gauge are similar to the corresponding parts of the upper air valve gauge and are designated by corresponding reference characters. The shoulders 14 of the lower air valve gauge are spaced apart for distances less than the diameter of the groove 40 so as to permit the gauge to be applied to the lower end of the cylinder as shown in Figure 6.

To ascertain the lift of the lower air valve 34, the valve cage 36 is removed from the cylinder, and the gauge is applied to the cylinder in a manner to position its cross bar 10a against the lower end thereof and across the opening 37, as shown in Figure 6. 40 In applying the gauge care must be taken to arrange the shoulders 14 in the groove 40 worn in the lower end of the cylinder by the cage flange 38. As the gauge is applied to the cylinder, the set screw 20 is turned back so as to free the tube 17a for upward movement to position the plug head 23 in contact with the cylinder of the upper wall of the valve chamber 35. The set screw 20 is now turned up to secure the tube 17a

45 against movement from the position it now occupies on the cross bar 10a. After this has been done, the gauge is applied to the valve cage 36 in a manner to position the free ends of its legs 12a in contact with the upper side of the cage flange 38. While this is being done the graduated bar 24 is held pressed into the tube 27a so as to insure the full contact of the legs 12a with the cage flange 38. After the gauge has been applied to the valve cage 36, 50 the graduated bar 24 is released so as to permit it to be moved by the spring 28 into contact with the center of the upper side of the valve 34. When the graduated bar 24 comes to rest by contacting with the upper side of the valve 34, that graduation 30 lo-

cated nearest the small end of the conical tube portion 21 will indicate the lift of the lower air valve 34. The space between the zero and third graduation is used for the purpose of ascertaining when the lower air valve is blind; that is, when the air valve lifts less than three-thirty-seconds of an inch. When the graduated bar 24 comes to rest with its third graduation in alinement with the lower end of the tube portion 21, the lift of the valve is correct. The space between the third and innermost graduations is for the purpose of ascertaining the over lift that all worn valves generally have.

55 From the foregoing description, taken in connection with the accompanying drawings, it should be apparent that the upper air valve gauge and the lower air valve gauge are similar except as to the relative proportions of certain parts thereof, that both gauges are used in substantially the same manner to ascertain the lift or lifts of the valves, and that both gauges provide a simple and easily performed method of ascertaining the lift or lifts of the valves. As 60 the bar 24 is provided at diametrically opposite sides thereof with graduations, each gauge may be read from either side thereof. By removing the plugs 23 and 23a, the 65 springs 28 and graduated bars 24 may be removed from the tubes 17 and 17a for the purpose of cleaning the springs, bars and the inner sides of the tubes. The lower air valve 70 34 wears away the top wall of the chamber 35 during the unseating thereof, and the tapped hole 41 in the upper side of this valve forms a projection 42 on the cylinder of said chamber which is received by the recess of the plug cap 23 when the lower air valve gauge is 75 applied to the cylinder.

80 While I have described the principle of the invention, together with the structure which I now consider the preferred embodiment thereof, it is to be understood that the structure shown is merely illustrative and that such changes may be made, when desired, as fall within the scope of the invention as claimed.

85 What is claimed is:—

90 1. A gauge of the character set forth, comprising a bar, legs extending in a common direction from one side of the bar, a tube passing through the bar for endwise adjustment with respect to the opposite side of the bar, 95 means for securing the tube in adjusted position, and a graduated bar slidable freely in the tube and extending from one end thereof in the general direction of the extension of the legs, said end of the tube cooperating 100 with the graduations on the bar as a pointer.

105 2. A gauge of the character set forth, comprising a bar, legs extending in a common direction from one side of the bar, a tube passing through the bar for endwise adjustment with respect to the opposite side of the 110

bar, means for securing the tube in adjusted position, a graduated bar slidably freely in the tube and extending from one end thereof in the general direction of the extension of the legs, said end of the tube cooperating with the graduations on the bar as a pointer, and a spring holding the graduated bar in extended position with respect to the tube.

3. A gauge of the character set forth, comprising a bar, legs extending in a common direction from one side of the bar, a tube passing through the bar for endwise adjustment with respect to the opposite side of the bar, the tube being provided in its outer side with a longitudinal groove, an element carried by the bar and engaging in the groove to hold the tube against rotation with respect to the bar, means for securing the tube in adjusted position, and a graduated bar slidably freely in the tube and extending from one end thereof in the general direction of the extension of the legs, said end of the tube cooperating with the graduations on the bar as a pointer.

4. A gauge of the character set forth, comprising a bar having an enlarged central portion provided with an opening, legs extending in a common direction from one side of the bar and arranged at opposite sides of said opening, a tube mounted in said opening for endwise adjustment with respect to the opposite side of the bar, the tube being provided in its outer side with a longitudinal groove, a rib on the wall of said opening and engaging in said groove to hold the tube against rotation with respect to the bar, a set screw carried by the enlarged portion of the bar and engaging the tube to secure the latter in adjusted position, and a graduated bar carried by the tube and extending therefrom in the general direction of the extension of the legs.

5. A gauge of the character set forth, comprising a bar, legs extending in a common direction from one side of the bar, a tube extending through the bar and adjustable in an endwise direction with respect to the opposite side of the bar, that end of the tube located beyond said first side of the bar being reduced and of conical formation, a graduated bar carried by the tube and extending through said end thereof which co-operates with the graduations as a pointer, the tube being provided in its inner side with a longitudinal groove, a head secured to the inner end of the graduated bar and provided with a rib slidably engaging in said groove to hold the tube against rotation with respect to the bar, a plug carried by the opposite end of the tube, a spring positioned between the plug and the head of the graduated bar, and means for securing the tube in adjusted position.

6. A gauge of the character set forth, comprising a bar, legs extending in a common direction from one side of the bar, a tube ex-

tending through the bar and adjustable in an endwise direction with respect to the opposite side of the bar, that end of the tube located beyond said first side of the bar being reduced and of conical formation, a graduated bar carried by the tube and extending through said end thereof which co-operates with the graduations as a pointer, the tube being provided in its inner side with a longitudinal groove, a head secured to the inner end of the graduated bar and provided with a rib slidably engaging in said groove to hold the tube against rotation with respect to the bar, a plug carried by the opposite end of the tube, a spring positioned between the plug and the head of the graduated bar, and means for securing the tube against rotation with respect to the bar.

7. A gauge of the character set forth, comprising a bar, legs extending in a common direction from one side of the bar, a tube extending through the bar and adjustable in an endwise direction with respect to the opposite side of the bar, that end of the tube located beyond said first side of the bar being reduced and of conical formation, a graduated bar carried by the tube and extending through said end thereof which co-operates with the graduations as a pointer, the tube being provided in its inner side with a longitudinal groove, a head secured to the inner end of the graduated bar and provided with a rib slidably engaging in said groove to hold the tube against rotation with respect to the bar, a plug carried by the opposite end of the tube, a spring positioned between the plug and the head of the graduated bar, means for securing the tube against rotation with respect to the bar, the legs being provided with concave inner sides and the bar being provided at said opposite side thereof with inwardly offset arcuate shoulders, and the graduated bar and plug being provided in their outer ends with concave recesses.

In testimony whereof I hereunto affix my signature.

PETER A. ALONZO.
